DESIGN FOR A TOILET BOWL DEODORIZER

Elliot A. Miller, New York, N. Y.

Application February 10, 1937, Serial No. 67,570

Term of patent 14 years

To all whom it may concern:

Be it known that I, Elliot A. Miller, a citizen of the United States and resident of New York, in the county and State of New York, have invented a new, original, and ornamental Design for a Toilet Bowl Deodorizer, of which the following is a specification, reference being had to the accompanying drawing, forming part thereof.

In the drawing:

Fig. 1 is a rear perspective view of a toilet bowl deodorizer showing my new design.

Fig. 2 is a front elevation thereof.

Fig. 3 is a side elevation of the same.

Fig. 4 is a bottom plan view thereof.

I claim:

The ornamental design for a toilet bowl deodorizer substantially as shown.

ELLIOT A. MILLER.
